UNITED STATES PATENT OFFICE.

JOHN J. HERBERT, OF CHATTANOOGA, TENNESSEE.

KNOCKDOWN CRATE.

SPECIFICATION forming part of Letters Patent No. 442,225, dated December 9, 1890.

Application filed September 11, 1890. Serial No. 364,600. (No model.)

To all whom it may concern:

Be it known that I, JOHN J. HERBERT, of Chattanooga, Hamilton county, Tennessee, have invented a new and useful Improvement 5 in Shipping Cases or Crates; and I do hereby declare that the following is a full, clear, and exact description of the same, which will enable others skilled in the art to which it relates to make and use the invention, reference being had to the accompanying drawings, forming part of this specification.

My invention relates to an improvement in shipping cases or crates; and it consists in the peculiar construction and combination of 15 devices, that will be more fully set forth hereinafter, and particularly pointed out in the claims.

In the accompanying drawings, Figure 1 is a perspective view of a shipping-case embodying my improvements. Fig. 2 is a side elevation of the same, partly in section. Fig. 3 is partly an end view and partly a section. Figs. 4 and 5 are detailed views.

The bottom A of the case or crate has cross-cleats B at its ends and a similar cleat at its center. The ends of these cleats project a sufficient distance from the sides of the bottom and are sheathed with metallic plates C to prevent wear. The sides D of the case are 25 provided with vertical cleats E, which are securely nailed or screwed thereon, and said cleats E project at their upper and lower ends, as shown, and are provided with sheath boxes or extensions F, made of sheet metal 30 and adapted to receive the ends of the cleats on the bottom and top of the crate when the same is assembled, as will be presently described. Rabbets G are cut on the inner sides of the end cleats E at suitable points 35 near their upper and lower ends.

The ends H of the case or crate are adapted to fit between top and sides and are provided with transverse horizontal cleats I, the ends of which project sufficiently to lap over the 40 end edges of the sides D, and said cleats I have their ends covered with metallic straps K, which are bent in the form of a right angle and have their ends, which project at right angles from the cleats I, provided on 45 their lower edges with notches L, whereby they constitute hooks, and the said notches

are adapted to engage nails or pins M', which pass centrally across the rabbets G of cleats E.

The top M of the case or crate is provided with transverse cleats N at its ends and center. The said cleats have one end sheathed with plates O, adapted to enter the upper sheath boxes or extensions F of the cleats E on one side of the case or crate, and at the other ends of the cleats N are plates P, having pairs of ears R, bent at right angles, which ears depend from the ends of the cleats and are adapted to receive the upper ends of the proximate cleats E. In said cleats E and in the said ears are made aligned openings S, adapted to receive pins T or other suitable fastening devices to secure the top firmly in place. I prefer to employ wires U, passed through said openings in the said cleats and ears, and seals V to secure the ends of 70 the wires together, and when thus secured the crate is not likely to be opened by a dishonest person during transit, and the seals would first have to be destroyed, and the fact would be betrayed.

It will be understood that the crate or shipping-case is capable of being readily taken to pieces and packed in a very small compass when being returned to the shipper, thereby saving freight charges.

The cleats employed on the bottom, top, sides, and ends of the crate render the same very strong and durable, and hence the said bottom, top, sides and ends may be made of very thin boards, thus effecting a considerable economy in the manufacture of the crate, and also making the same very light, and hence lessening the freight charges thereon when in transportation. The boxes F are provided on their inner sides at their ends 85 with shoulders W, which are engaged by lips X, formed by turning out the ends of the plates C O. These shoulders and lips serve to more firmly secure the cleats together at their joints.

Having thus described my invention, I claim—

1. In a crate or case, the surrounding cleats adapted to be attached respectively to the bottom, sides, and top, said cleats being provided at their meeting ends with the metallic extensions or boxes F, having the shoul-

ders W, and the plates C, having the lips X to engage said shoulders, all arranged to operate substantially as described.

2. In a case or crate having the detachable top, bottom, sides, and ends, the surrounding cleats B E M, having the fastening devices at their meeting ends, said cleats E being further provided with the rabbets G and the pins or nails M' passing through them, and the ends having the cleats I, with right-angled straps K at their ends, said straps being adapt-

ed to enter the rabbets G, and having notches L to engage the pins or nails M', whereby the ends are secured in place, substantially as described.

In testimony that I claim the foregoing I append my signature.

JOHN J. HERBERT.
